BRASSIÈRE

Fay Edith Everitt, Santa Monica, Calif.

Application February 26, 1947, Serial No. 730,961

2 Claims. (Cl. 2—42)

1

This invention relates to undergarments of the general class including brassières, corselets, and foundation garments. The general object of my invention is to provide a garment of this type which has an improved cup construction which will provide greater comfort to the wearer than brassières of conventional design.

Another object of my invention is to provide a garment of this type having improved ability to prevent sagging and breaking down of the breasts.

Another object is to provide a garment of this type which will lie smoothly beneath an outer garment to give an improved and more natural appearance to the body contour.

A further object is to provide such a garment which will relieve the strained feeling that ordinarily accompanies the wearing of a conventional brassière or the like.

Other objects of the invention will become apparent in the ensuing specifications, considered in connection with the appended drawings, in which:

Fig. 1 is a front view of a brassière embodying my invention;

Fig. 2 is a profile of the bust of a person wearing my improved brassière;

Fig. 3 is a bust profile with my improved brassière shown in section;

Fig. 4 is a view of the triangular portion of material removed from the cup portion of my improved brassière, illustrating the shape thereof; and

Fig. 5 is a front view of the invention embodied in a different type of brassière.

As an example of one form in which the invention may be embodied, I have shown in Figs. 1 to 3 inclusive a brassière of a type commonly worn by women of mature age, in which a pair of breast cups 6 generally conoidal in shape, are mounted in a waist band or belt 7.

Each of the cups 6 includes a lower wall portion 8 which is shaped to correspond generally to somewhat less than a quarter section of a spherical surface. The lower edge of each wall portion 8 is joined by a semi-circular seam 9 to the edge of a cutout in the waist band 7. Each wall portion 8 has a hemstitched free upper edge including a central, curved portion 10 and downwardly inclined portions 11 and 12. Joined to the outer extremities of the upper edges of the wall section 8 by seams 13 and 14 are upper wall sections 15 and 16. The wall sections 15 and 16 are formed in a single piece of material and are inclined upwardly and toward each other. Their

2

lower inner corners are cut away to provide diagonal edges 18, 19 respectively, which are machine finished (e. g., hemstitched, picoted, or overcast) but are not bound. They are arched in surface contour so as to cooperate with the lower wall section 8 in defining a generally conoidal shape in the cup 6.

The edges 10, 11, 12, 18, and 19 cooperate to define a generally triangular-shaped aperture 20 in each of the cups 6. The center of the base portion of each aperture (defined at the apex of the arched edge portion 10) lies substantially at the apex of the conoidal surface of the cup 6. The base edge of the triangular space 20 is arched upwardly from the two base corners thereof, such arching corresponding to the inclination of the edges 11 and 12 and the arched shape of the edge portion 10. As viewed from above, along a line of sight (indicated by the arrow 21), inclined downwardly and substantially lying in the plane of the edges 13 and 14, however, the aperture 20 will appear triangular in shape.

The apex portion of the lower wall section 8, indicated by the numeral 22, has a double-curved shape produced by gathering the material of the wall 8 in a dart 17, and extends upwardly to completely cover and form a support for the nipple 23 of the breast 24 that is supported in the cup 6. The apex portions 22 in effect constitute flaps or tongues which, because of their double curved shape, are form retaining but which at the same time are sufficiently flexible to yield inwardly under the pressure of the outer garment (such as a blouse or waist), that is worn over the brassière, so as to provide a smoothly curved contour devoid of pointed protrusions such as are commonly produced by the apices of the cups of a conventional brassière. Darts 17a, substantially aligned with the central longitudinal axes of the straps 25, extend upwardly from the apices of the apertures 20. Shoulder straps 25 are attached at their respective ends to the upper extremities of the cups 6 and to the portions 26 of the waist band 7 which extend around the back of the wearer. The apices of the apertures 20 are in substantial alignment with the center lines of the straps 25. As a result, the weight of each breast is transmitted equally from both sides thereof upwardly and inwardly through the upper wall members 15 and 16 of the cup supporting that breast, to the strap which in turn supports the cup.

Since the weight is transmitted upwardly from the sides of the breast and there is no upward pull against the flap portions 22, the entire pe-

riphery of each breast from the bottom to the side regions thereof is lifted and moulded away from a sagging shape and toward a conical shape. Accentuated, point-like protrusions at the apices of the breasts are, however, avoided because of the slight inward yielding of the flap portions 22, under the tension in the edge 10, 11, 12, and under the light pressure of the outer garment worn over the brassière. The tension in the edge 10, 11, 12 is effective to urge the flap member 22 inwardly (or, more accurately, to restrain the flap member against outward bending, because the seams 13 and 14 combine with the free edge 10, 11, 12 to constitute in effect an arched, catenary-like tension member anchored at both ends (in the seam 9) and therefore constraining inwardly at all points along the length thereof in opposition to the outward pressure of the breast. Consequently, the flap member 22 tends to induce a smooth, non-pointed curvature in the apex of the cup, unaided by the pressure of the outer garment, and such pressure only serves to add to the rounding effect in accordance with the conformation and tightness of the outer garment. At the same time, the catenary arch effect of the tension member enables the flap member 22 to provide sufficient support for the apices of the breasts to support them in lifted positions without pointing. The overall effect is to mould the breasts to shapes most nearly approaching a natural, youthful form, most highly desired.

Since the weight is transmitted to the straps 25 solely along diagonal paths extending upwardly from the side regions of the lower wall section 8 and there is no upward pull against the central or apex portion of the cups, a considerable amount of discomfort that is caused by such direct central pull in the conventional brassière is avoided, and the brassière of my invention is therefore much more comfortable to the wearer than the conventional brassière.

The waistband 7 terminates in back straps 26 which are adapted to be secured together at their ends by a conventional hook and eye or other equivalent fasteners 27.

The upper extremity of the garment is defined by diagonal edges 28 extending upwardly and outwardly from the center of the brassière and diagonal edges 29 extending downwardly and outwardly from the strap 25. These edges, and the lower edge of the waistband 7 are hem-stitched, picoted, or otherwise bound without using binding tape or other binding of a heavy nature.

In Fig. 5 I have shown a brassière for a more petite figure, embodying cups 6a having adjacent corners crossed and secured at 31 at the center of the brassière, having shoulder straps 25a secured to their upper extremities and waist straps 26a secured to their outer extremities. Each of the cups 6a are constructed from a single piece of fabric, with a sector thereof removed to define edges which are secured together by a seam 32 extending downwardly from the center of the base edge 10, 11, and 12 of the aperture 20, to produce the conoidal shape of the cup. The cups 6a are provided with apertures 20 defined on their lower sides by flap portions 22 which, as in the other form of the invention, extend above the apices of the cups and are adapted to completely cover and support the nipples. The edge portions 10, 11, and 12, 18 and 19 are similar in arrangement and in their relation to the cups 6a, to the relationship described in connection with the main form of the invention.

5 It may now be noted that in the invention, the triangular-shaped openings of the cups lie entirely in the upper sides of the cups, i. e., above the apices of the cups. The base of each opening is arched, with the side regions thereof sloping downwardly.

10 The relative proportioning of the dimensions of the apertures to each other and to the cup dimensions is important. I find that, for the best results, the distance X between the corners of the apertures (the base dimension), should be between 1.5 and 2.0 times the distance Y from the base to the apex of the aperture. As a specific example of such dimensions, the size of the piece of material 35 cut out of an aperture 20, may 15 for a size 36 brassière or larger be such that the base dimension X (Fig. 4) is 3 1/4 inches while the height Y is 2 inches. For sizes 34 and smaller I prefer to make the cutout 1/8 inch narrower along 20 each of the edges 18 and 19. Fig. 1 of the drawing illustrates accurately the preferred proportioning of aperture and cup dimensions.

25 Actual tests have proven that a brassière constructed in accordance with my invention is superior to conventional brassières from the standpoint of increased comfort to the wearer, preventing the sagging and breaking down of breasts, preserving naturalness, and avoiding undesirably pointed protrusions at the apices of the cups. 30 My brassière relieves both shoulder and breast strain while at the same time molding the breasts to a most desirable natural shape. As to the relieving of shoulder strain, it has been my experience that the conventional brassière produces the feeling of the shoulders being dragged forwardly and downwardly, especially when the brassière is attached to or part of a foundation garment. My invention eliminates this dragging sensation and improves posture, by leaving the shoulders and chest unrestrained.

35 The double curvature of the lip portion 22 is such that the upper extremity thereof curves back over the nipple sufficiently, and extends upwardly to a sufficient height relative to the remainder of the cup, so that the nipple is retained during all normal body and arm movements and even during exercising activities, and is not permitted to slip into the aperture 20.

40 I claim:

1. In a garment of the brassière type, a breast cup including a lower wall section of sheet fabric and a pair of sheet fabric wall portions joined by seams to the side extremities of said lower wall section and converging upwardly, said pair of wall portions having downwardly and outwardly diverging lower inner edges spaced from said lower wall section to define a triangular opening, said lower wall having an upper portion having an upwardly arched upper edge defining the base of said opening, said upper portion constituting the apex portion of said cup and providing a yielding support for the apex of the breast, arranged to completely cover the nipple thereof.

45 2. In a garment of the brassière type, a breast cup of sheet fabric including a lower section and an upper section, said upper section including downwardly diverging portions having downwardly diverging lower inner edges spaced from said lower wall section to define a triangular opening, said lower wall having an upper portion having an upwardly arched upper edge defining the base of said opening, said upper portion constituting the apex portion of said cup and providing a yielding support for the apex of the

breast, arranged to completely cover the nipple thereof.
